UNITED STATES PATENT OFFICE.

JAMES D. CAMPBELL AND WALTER T. TUCKER, OF DUNCAN, OKLAHOMA.

COOLING-FAN ATTACHMENT FOR CUSHION SEATS.

Application filed October 7, 1924. Serial No. 742,191.

To all whom it may concern:

Be it known that we, JAMES D. CAMPBELL and WALTER T. TUCKER, citizens of the United States, residing at Duncan, in the 5 county of Stephens and State of Oklahoma, have invented certain new and useful Improvements in Cooling-Fan Attachments for Cushion Seats, of which the following is a specification.

10 This invention relates to improvements in a cooling fan attachment for cushion seats, whereby the back of the occupant of the seat will be kept cool.

One of the important objects of the present invention is to provide a device of the above mentioned character, which is adapted to be used in conjunction with barber chairs and also in connection with the cushion seat of an automobile.

20 A still further object of the invention is to provide a device of the above mentioned character, which is so associated with the cushion seat, as to not cause any discomfort to the occupants thereof, the device being 25 simple in construction, inexpensive, strong and durable, and further well adapted for the purpose for which it is designated.

Other objects and advantages of this invention will become apparent during the 30 course of the following description.

In the accompanying drawing, forming a part of this specification, and in which like numerals designate like parts throughout the same:

35 Figure 1 is a perspective view of the device embodying our invention, showing the same associated with a barber's chair.

Figure 2 is a vertical sectional view of the air distributor, showing the manner in which 40 the same is associated with the rear portion of the seat cushion.

Figure 3 is a top plan view, and

Figure 4 is a side elevation showing the device used in conjunction with the seat 45 cushion of an automobile.

In the drawing, wherein for the purpose of illustration is shown the preferred embodiment of our invention, the numeral 1 designates the air distributor, the same comprising a casing, the sides of which converge toward the top, the top 2 of the casing comprising the air distributor 1 being provided with a series of spaced openings 3. The air distributor casing is of such shape as to conform to the contour of the seat cushion with

55 which the same is associated, and, as is

shown in Figures 1 and 3 of the drawings, the distributor casing is substantially of arcuate design.

When used in conjunction with the barber 60 chair, the distributor casing is disposed at the rear of the seat cushion 4, the body of the distributor casing resting on the seat supporting frame 5, while the top of the casing is slightly curved to conform to the 65 curved edge of the seat cushion, and furthermore the top of the casing is disposed substantially flush with the upper edge of the seat cushion, so that the occupant of the 70 chair may be seated therein in a comfortable 75 position. Cooperating with the air distributor 1 is the casing 6, which is secured to the chair frame 5, at the rear thereof by the supporting brackets 7, a rotary fan 8 of any well known construction being supported in 80 the casing. A flared nozzle 9 is secured to the casing 6 for communication with the fan 8, while the smaller end of the nozzle is disposed through a suitable opening provided in the frame 5 and extends into the central 85 portion of the bottom of the air distributor 1. This construction permits the air entering the casing 6 through the opening 10 to be forced out through the nozzle 9 and into the distributor 1, by means of the rotary 90 fan, so that cool air may be forced out through the opening 3 in the top 2 of the distributor casing 1, causing the air to pass up the back of the occupant of the chair.

The cooling device is further adapted to 95 be used in conjunction with the seat cushion of automobiles, and as is illustrated more clearly in Figure 4 of the drawing, the air distributor casing 1 is disposed at the rear of the seat cushion adjacent the backs of the 95 seat, so that the occupants of the seat will have the full benefit of the air which is forced through the opening provided in the top of the distributor casing, in the manner as above described. A cooling device of 100 the character above described is especially adapted to be used in connection with cushions of automobiles, during the warm weather and when the motor of the fan is in operation, a continuous flow of cool air will 105 pass up the back of the occupant of the seat, whereby a comfortable position may be maintained, and further preventing the clothes of the occupant of the seat from sticking to the back of the seat.

110 The simplicity in which our cooling device is constructed enables the same to be

readily and easily attached in position for use, and may be used in conjunction with various pieces of furniture upon which persons are adapted to be seated.

5 While we have shown the preferred embodiment of our invention, it is to be understood that various changes in the size, shape, and arrangement of parts may be resorted to, without departing from the spirit of the 10 invention and the scope of the appended claims.

Having thus described our invention, what we claim is:

1. A device of the class described comprising in combination with a seat cushion, 15 an air distributor supported at the rear thereof and conforming to the configuration of the seat cushion, said distributor comprising a casing, the top thereof being provided with a series of spaced air outlet 20 openings, a nozzle having its upper end extending into the bottom of the air distributor casing, a casing associated with the bottom of the nozzle, said casing having air inlet openings provided therein, and a rotary fan mounted in the casing and communicating with the nozzle.

municating with the bottom of said nozzle for forcing the air upwardly therethrough 25 and through the openings in the top of the air distributor casing.

2. A device of the class described comprising in combination with a seat cushion, 30 an air distributor supported at the rear thereof and conforming to the configuration of the seat cushion, said distributor comprising a casing, the top thereof being provided with a series of spaced air outlet 35 openings, a nozzle having its upper end extending into the bottom of the air distributor casing, a casing associated with the bottom of the nozzle, said casing having air inlet openings provided therein, and a rotary fan mounted in the casing and com- 40 municating with the nozzle.

In testimony whereof we affix our signatures.

JAMES D. CAMPBELL.
WALTER T. TUCKER.
